United States Patent Office

Des. 199,841
Patented Dec. 22, 1964

199,841

PICTURE HOOK OR SIMILAR ARTICLE

Joseph M. Margulis, % Jiffy Enterprises, Inc.,
150 N. 13th St., Philadelphia, Pa.

Filed Dec. 4, 1962, Ser. No. 72,705

Term of patent 14 years

(Cl. D17—12)

FIG. 1

FIG. 2

FIG. 5

FIG. 6

FIG. 3

I claim:

The ornamental design for a picture hook or similar article, substantially as shown.
